AUTOMATIC LIQUID FUEL DISPENSER

Filed March 28, 1928

UNITED STATES PATENT OFFICE

CHARLES BRAHY, OF BROOKLYN, NEW YORK, ASSIGNOR TO CHARLES E. MARION, OF NEW YORK, N. Y.

AUTOMATIC LIQUID-FUEL DISPENSER

Application filed March 28, 1928. Serial No. 265,257.

This invention relates to a liquid fuel dispenser of the type operated by a coin-actuated mechanism; the object being to provide a machine that will automatically dispense a given quantity of liquid fuel, such as gasoline, by the insertion of a coin into a slot in the machine. Another object is to provide means to prevent the operation of the machine by a coin other than that of a predetermined 5 nomination. A further object of this invention is to provide adjusting means, in a machine of this class, to vary the quantity of fuel dispensed, in accordance with price fluctuations, and to render the machine adaptable to 10 be set for dispensing different quantities of fuel for different coins.

Referring to the drawings:

Figure 1 is a front sectional elevation of the apparatus constituting the invention. 20 Figure 2 is an enlarged fragmentary sectional elevation of the coin-operating mechanism.

In the drawings, 1 represents the coin-slot communicating with the chute 2, which is positioned over the temporary coin receptacle 3. This receptacle is pivotally connected at 4, and is yieldably held against rotation by the hair spring 5. The balanced support 6, mounted on pivot 7, has fitted thereon the 25 hair spring 8, adjusted to yieldably hold said support against rotation. The arm 9 is fixed to pivot 7, and contains a slot 10 within which is slidably positioned the pin 11 secured to the link 12. The arm 13 of the lever mounted 30 on shaft 14 is pivotally attached to the link 12, and the arm 15 is pivotally attached to the tripper rod 16. Over this rod is the helical spring 17 positioned within compartment 18. the said tripper rod is pivotally attached to 35 the lever 19 which is pivotally mounted at 20, one arm of the said lever being pivotally attached to the link 21 which is connected to the arm 22 of the meter 23; the other arm of the said lever 19 being positioned near the 40 wheel 24 on which the tripper finger 25 is suitably fixed.

The electric motor 26 is connected to pulley 27 by the belt 28, the shaft 29 of said pulley containing a pinion the teeth of which 45 are in engagement with those on the wheel 24.

The wheel 24 is mounted on shaft 30 which is supported by the bearing 31 mounted on the support 32 which is suitably secured to the housing 33. The wheel 24 is provided with the slot 34 within which is slidably fitted the pin 35 which is provided with means to immovably hold said pin in any predetermined position within said slot. One end 36 of the connecting rod 37 is mounted on the pin 35, the other end 38 being pivotally connected at 39 to the piston rod 40 of the pump plunger 41. The gasket 42, positioned around the periphery of the said plunger, is fitted thereon in such manner as to allow a proper sliding movement of the plunger within the 55 cylinder 43. The fuel supply pipe 44 communicates with inlet openings 45 and 46 through the one-way valves 47 and 48; and the outlet openings 49 and 50 communicate, through one way valves 51 and 52, with the 60 hose 53.

Two electric conductors 54 and 55 lead from a main source of current supply 56 to the motor 26 and the contact point 57 respectively, the said contact point 57 being attached to the spring 59 and to the magnet 60 of the solenoid 61. Adjacent to said point 57 is the contact point 58 which is electrically connected, by conductor 62, to the motor 26. The solenoid 61 is electrically connected, by 65 line 63, to the auxiliary source of current supply 64, and by line 65 to contact point 66, which is secured to the said support 6. The contact point 67, secured to the said receptacle 3, is electrically connected, through conductor 69, to said auxiliary source of current supply 64. The lamp 70 is connected, by electric conductors 72 and 73, to the line 63 and the contact point 68, which is in contact with the point 67 when the apparatus is in its normal 70 starting position.

When a coin is deposited into slot 1, it slides down the chute 2 and is deposited into the temporary receptacle 3. The weight of the coin causes the said receptacle to swing downwards, in a clockwise direction, around the pivot 4, against the action of the spring 5, until the contact point 67 comes into abutment with contact point 66, the spring 7 being adjusted to enable the support 6 to up- 75 80 85 90 95 100

hold the superimposed receptacle 3 with the proper coin therein. When the contact points 66 and 67 are thus brought together, the circuit through the auxiliary source of current supply 64 and the solenoid 61 is closed, thereby causing the magnet 60 to be drawn in, against the action of the spring 59, thereby bringing together contact points 57 and 58. This closes the circuit through the motor, thereby operating the pump plunger through the medium of the belt 28, pulley 27, wheel 24, connecting rod 37, and piston rod 40.

As the wheel 24 completes a revolution, the tripper finger 25 trips the lever 19, thereby causing the rod 16 to move in the direction of the arrow and causing the link 12 to move upwards. This causes the arm 9 and consequently the pivot 8 to rotate in a counter-clockwise direction, carrying with it the support 6. The receptacle 3 is now allowed to continue on its downward course, swinging about the pivot 4 until the coin 77 is dropped through the chute 74 into the coin box 75. When the receptacle 3 is thus relieved of the weight of the coin, the spring 5 will carry the said receptacle back to its starting position, thereby causing the contacts 66 and 67 to separate. This breaks the circuit through the solenoid 61, and consequently cuts off the current through the motor, whereby the machine is brought to a stop.

When the machine is not in operation, the contacts 67 and 68 are in abutment, so that the current from the source 64 keeps the lamp lighted. As soon as a coin is deposited within the receptacle 3, and it begins to swing downwards due to the weight therein, the contacts 67 and 68 are separated, shutting off the current through the lamp, thereby indicating that the machine is in operation.

If a coin smaller than that of the predetermined denomination is deposited, it will drop down through the space between 78 and 45 79, and into the coin box, without operating the machine.

The spring 5 is adjusted so that it will not yield under the weight of a coin that is lighter than a coin of a predetermined denomination. If the weight is greater, the receptacle 3 will swing downwards as before, but the added weight will cause the support 6 to swing downwards also, around the pivot 8, as the spring 7 is adjusted to hold no more than the weight of the proper coin. The receptacle 3 will continue to swing downwards until the coin drops down into the chute 74 and into the coin box 75; and the said receptacle, now being relieved of the weight of the coin, will return to its normal position. When the contacts 66 and 67 are thus momentarily brought into contact, the circuit through the solenoid 61 is closed, but it is broken again before the slow-moving magnet 60 establishes contact between points 57

and 58, and in this way preventing the motor from operating.

If there is but one tripper finger 25 on the wheel 24, the plunger 42 will make one up and one down stroke, thereby supplying a corresponding amount of fuel through the hose 53. But if another tripper finger 76 is secured to the wheel 24 diametrically opposite finger 25, the tripping action will take place every half a revolution of the wheel 24, so that the plunger will make either one up or one down stroke for each coin deposited. In this way the machine can be set for a coin of a given denomination, or for one of half that denomination.

Each tripping action will simultaneously operate the tripping rod 16, and the meter 23 through the link 21 and arm 22. This meter will thus indicate the number of coins deposited, thereby serving as a check-up.

To make an adjustment for fluctuating fuel prices, the pin 35 can be fixed anywhere along the slot 34, thereby varying the length of stroke of the plunger 41, and in this way controlling the amount of fuel supplied per coin deposited. The one-way valves 47, 48, 51, and 52 permit a unidirectional flow of fuel from the main supply pipe 44 to the hose 53.

The drawings and description herein refer to but one of several different mechanical forms and constructions that may be embodied in my design.

What I claim is:

1. In an automatic liquid fuel dispenser of the class described a coin-operated control box comprising, in combination, a coin-deposit slot communicating with a chute terminating above a temporary coin receptacle having an electric contact point attached thereto; an intermediate releasable support for said receptacle, the said support having another electric contact point attached thereto; said receptacle being provided with means to enable the weight of a coin deposited therein to cause a downward movement of said receptacle until it comes into abutment with and rests upon said releasable support thereby bringing said points into contact with each other; means to trip said releasable support and remove it from its position where it upholds said receptacle, thereby separating said contact points and at the same time allowing said receptacle to continue on its downward course until the coin therein is caused to drop into a suitably positioned coin box; and means to bring said receptacle and said support back to their starting positions.

2. In an automatic liquid fuel dispenser of the class described a coin-operated control box containing a coin deposit slot communicating with a chute terminating above a pivotally connected coin receptacle provided with means to yieldably hold said receptacle against rotation; a pivotally connected inter-

mediate support provided with balancing means to yieldably hold said support against rotation, the said support being positioned with respect to the said receptacle in such manner that when said receptacle is caused to rotate about its pivot due to the weight of a coin deposited therein, one end thereof will come into contact with and rest upon said support, the said balancing means being adjusted to cause said support to yield when the coin within the superimposed receptacle is of greater than a predetermined weight, thereby releasing said receptacle from its support and permitting it to continue on its downward course until the coin therein is caused to drop into a suitably positioned coin box.

3. In an automatic liquid fuel dispenser of the class described, a motor-driven liquid fuel pump; a pair of adjacent contact points in series with the motor of said pump and a main source of current supply; electro-mechanical means mechanically connected to said contact points and provided with slow-operating means adapted to gradually bring said points into contact with each other; a yieldably supported and balanced coin receptacle; means to cause said receptacle, when a coin is deposited therein, to close the circuit through said electro-mechanical means; and means to cause the said balanced receptacle, when the coin deposited therein is of greater than a predetermined weight, to break the circuit through said electro-mechanical means before said slow-operating means bring the said points into contact.

In witness whereof I affix my signature.
CHARLES BRAHY.
